UNITED STATES PATENT OFFICE.

HANS PASCOLINI, OF CHICAGO, ILLINOIS.

REVOLVING FLUID-PRESSURE MOTOR.

Application filed March 20, 1922. Serial No. 545,019.

To all whom it may concern:

Be it known that I, HANS PASCOLINI, a citizen of the United States, and a resident of Chicago, Cook County, Illinois, have invented a certain new and useful Improvement 5 in Revolving Fluid-Pressure Motors, of which the following is a specification.

This invention relates to rotary or revolving engines or motors in which there are cylinders having pistons therein, and in which the cylinders rotate or revolve about an axis, the pistons being connected to a stationary crank whereby in effect the pistons reciprocate in the cylinders, but only relatively, inasmuch as practically the entire engine or 10 motor revolves about the said axis and the pistons in effect move back and forth in the cylinders because said crank is eccentrically located and is some distance from said axis, and in reality the cylinders move toward and 15 away from said crank as they revolve.

Generally stated, the object of the invention is to provide an improved construction and arrangement whereby said pistons are 20 double-acting, so to speak, fluid pressure being admitted at opposite sides of each piston, whereby each piston is always exerting pressure on said stationary crank to cause the rotation or revolving motion of the 25 engine or motor.

It is also an object to provide an improved construction or arrangement whereby the engine or motor is reversible at will.

Another object is to provide certain details and features of construction tending to 30 increase the general efficiency and the desirability of a rotary or revolving engine or motor of this particular character.

To these and other useful ends the invention consists in matters hereinafter set forth and claimed and shown in the accompanying drawings in which—

Figure 1 is a vertical axial section (on line 1—1 in Figure 2) of an engine or motor embodying the principles of the invention.

Figure 2 is a section on line 2—2 in Figure 1.

Figure 3 is an enlarged detail section on line 3—3 in Figure 1.

Figure 4 is a similar section on line 4—4 in Figure 1.

Figure 5 is a similar section on line 5—5 in Figure 1.

Figure 6 is a similar section on line 6—6 in Figure 1.

Figure 7 is an enlarged side elevation of certain parts of the valve mechanism.

Figure 8 is a detail view of the interior portion of the mechanism shown in Figure 7, showing the omitted parts in dotted lines.

As thus illustrated, the invention comprises a plurality of cylinders 1 arranged as shown and preferably cast integrally with each other and secured at their outer ends to the annular member 2 which forms the rim of the wheel of which said cylinders are the spokes, which has the spokes 3 in addition, thus forming a body which is free to rotate on the bearing 4 carried by the stationary crank shaft 5, the latter being solidly mounted in the bearings 6, in the manner shown. A pulley wheel 7 can be secured to one side of the wheel like rotary body thus provided. Pistons 8 are provided in said cylinders, having piston heads 9, together with crossheads 10 which slide in the guides 11 to prevent lateral thrust on said piston rods. Crank 12 of said stationary crank shaft is connected by a pitman 13 with each crosshead 10, whereby fluid pressure exerted on the pistons in the cylinders will serve to rotate the wheel like body formed by the cylinders and spokes previously mentioned. For this purpose each cylinder is provided with ports 14 and 15 for admitting and exhausting the fluid pressure, such as steam or compressed air, to and from the cylinders to exert the necessary pressure on the pistons therein. Passages 16 and 17 connect the ports 14 and 15 respectively with the valve mechanism at the center of the engine, the fluid pressure being admitted to said mechanism through the pipe 18, and then admitted to said cylinders to operate the pistons therein. The fluid pressure is then exhausted from the cylinders through said 80 passages to said valve mechanism and is allowed to escape from the latter through the pipe 19, whereby pressure is first admitted to one side of each piston and then the other side thereof. In this way, as 85 previously stated, the engine is double acting, so to speak, inasmuch as the fluid pressure causes each piston to first exert a push and then a pull on the stationary crank shaft. In other words, power is developed 90 by each stroke of each piston, regardless of whether the piston is moving toward the inner end of the cylinder or toward the outer end thereof. For this purpose said valve mechanism comprises the cylindrical portion 20 of the stationary crank shaft. A 95 collar 21 is stationary on said portion 20

and is provided with openings 22 and 23 to communicate with the passages 17 of the engine. A similar collar 24 is mounted next to the collar 21 and is provided with openings 25 and 26 to communicate with the passages 16 previously mentioned. A third collar 27 is mounted next to the collar 24 and is provided with openings 28 and 29 to communicate with the pipes 18 and 19 previously mentioned. The collar 27 has a handle 30 and is adjustable by oscillation thereof to connect the opening 28 with the pipe 19, and to connect the opening 29 with the pipe 18, when it is desired to reverse the engine. Said cylindrical portion 20 is provided with a pair of grooves 31 and 32 for allowing the fluid pressure to pass from the opening 28 to the passages 16 and 17, as the engine rotates or revolves, and permit the exhaust to pass back from these passages 16 and 17 to the opening 9 previously mentioned; when the collar 27 is turned or oscillated to reverse its position, the fluid pressure then passes into the opening 29 and from the latter to the passages 16 and 17, and returns from the latter to the opening 28 and then out through the exhaust pipe 19, in a manner that will be readily understood. It follows, therefore, that the openings 22 and 23 and 25 and 26, and the grooves 31 and 32, must be so formed and relatively arranged that while pressure is passing into the engine through the passage 17 of one of the cylinders, the exhaust from this cylinder is passing out through the passage 16; and, vice versa, after the piston 8 arrives at the outer end of this cylinder, the fluid pressure must then pass into the cylinder through the passage 16 and the exhaust must pass out through the passage 17, said valve mechanism being constructed and arranged to thus alternately admit and exhaust the fluid pressure to each cylinder. Furthermore, the arrangement of the passages and openings and grooves of said mechanism is such that fluid pressure is always acting against either one side or the other of each piston, so that each piston is always contributing power to rotate or revolve the engine. It will be seen that the collars 21, 24 and 27 are tapered, and that the crank shaft has a screw nut 33 for pushing these tapered elements toward the engine to take up wear and prevent leakage. Thus the engine is double acting, as stated, each piston being capable of exerting first a push and then a pull on the stationary crank 12 which is eccentric to the axis of the engine. Also, the fluid pressure is admitted and exhausted at the axial center of the engines, and the rotation of the cylinders serves to automatically admit and cut off the fluid pressure, and to open and close the exhaust passages, in the manner described. It will be understood, of course, that the engine may have

any suitable or desired number of cylinders, one or more, and that the invention is not limited to the construction shown and described.

It will be seen that the collar 27, as previously explained, is oscillatory about the axis of the engine to reverse the motion of the engine, and by means of the handle 30 this collar 27 may be adjusted in position to throttle the steam somewhat thereby to reduce the speed of the engine when such is desired. In other words, the solid portions of the collar 27, shown between the two grooves 28 and 29 of the collar 27, can be adjusted in position to partially close the passages 18 and 19, thus slowing the engine down to the speed required. This is shown clearly in Figures 5 and 6 of the drawings, and it will be seen that the adjustable throttle valve is, therefore, a reversing valve as well.

What I claim as my invention is—

1. In an engine or motor, a cylinder mounted to revolve about an axis, a piston in said cylinder, adapted to reciprocate relatively therein, a stationary crank eccentric to said axis, means to connect the piston to said crank, means rigid with said crank to form a support for said cylinder, forming said axis, and rotary valve mechanism having rotary valve motion about said axis and controlled by the revolving motion of the cylinder to admit and exhaust fluid pressure to and from said cylinder at opposite sides of said piston, whereby said piston alternately exerts a push and then a pull on said crank to revolve the cylinder, said valve mechanism comprising grooves forming fluid passages in the stationary shaft portion of said crank.

2. In an engine or motor, a cylinder mounted to revolve about an axis, a piston in said cylinder, adapted to reciprocate relatively therein, a stationary crank eccentric to said axis, means to connect the piston to said crank, means rigid with said crank to form a support for said cylinder, forming said axis, and rotary valve mechanism having rotary valve motion about said axis and controlled by the revolving motion of the cylinder to admit and exhaust fluid pressure to and from said cylinder at opposite sides of said piston, whereby said piston alternately exerts a push and then a pull on said crank to revolve the cylinder, said valve mechanism comprising a stationary cylindric member upon which the engine rotates, with grooves in said member, collars on said member, with opposite openings in each collar, and passages to connect the cylinder with said openings, together with fluid pressure inlet and outlet means communicating with said grooves.

3. In an engine or motor, a cylinder mounted to revolve about an axis, a piston in

said cylinder, adapted to reciprocate relatively therein, a stationary crank eccentric to said axis, means to connect the piston to said crank, and valve mechanism controlled by the revolving motion of the cylinder to admit and exhaust fluid pressure to and from said cylinder at opposite sides of said piston, whereby said piston alternately exerts a push and then a pull on said crank to revolve the cylinder, said valve mechanism comprising a stationary cylindrical member upon which the engine rotates, with grooves in said member, collars on said member, with opposite openings in each collar, and passages to connect the cylinder

with said openings, together with fluid pressure inlet and outlet means communicating with said grooves.

4. A structure as specified in claim 3, said valve mechanism being adjustable to change the speed and also to reverse the engine.

5. A structure as specified in claim 3, said valve mechanism having a single handle by which said mechanism is adjustable about the axis of the engine to control the speed thereof and to reverse the direction of rotation.

HANS PASCOLINI.
